(57) **CLAIM**

We claim the ornamental design for an electronic percussion instrument stand, as shown and described.

DESCRIPTION

FIG. 1 is a front view of a electronic percussion instrument stand showing our new design, as attached to an electronic percussion instrument.

FIG. 2 is a rear view thereof.

FIG. 3 is a left side view thereof.

FIG. 4 is a right side view thereof.

FIG. 5 is a top view thereof.

FIG. 6 is a bottom view thereof.

FIG. 7 is a perspective view thereof, as also attached to a foot pedal.

FIG. 8 is a front view of the electronic percussion instrument stand.

FIG. 9 is a rear view thereof.

FIG. 10 is a left side view thereof.

FIG. 11 is a right side view thereof.

FIG. 12 is a top view thereof.

FIG. 13 is a bottom view thereof.

FIG. 14 is a cross-section view thereof, where the cross-section is taken along the line A-A of FIG. 8; and,

FIG. 15 is a cross-section view thereof, where the cross-section is taken along the line B-B of FIG. 8.

The ornamental design which is claimed is shown in solid lines in the drawings. The broken lines in the drawings are for illustrative purposes only and form no part of the claimed design.
